UNITED STATES PATENT OFFICE

JOHN HENRY BEEBY, OF MONTREAL, QUEBEC, CANADA, ASSIGNOR TO E. L. PATEAU, OF MONTREAL, QUEBEC, CANADA

GAS BURNER

Application filed June 18, 1928. Serial No. 286,211.

The present invention relates to improvements in gas burners and is a modification of my United States Patent No. 1,466,291, dated August 28th, 1923.

5 The main object of this invention is to provide means of readily adjusting the spreader in the burner to control the egress of gas at its exit end.

The invention is hereinafter fully described and claimed, and is illustrated in the accompanying drawing, in which a vertical section view through a burner according to the invention is shown.

Referring to the drawing, 1 is the body of 15 a burner and 2 is an upright extension terminating in an exit open end 3, having an inwardly bevelled seat 4. In the side of said body is provided an opening 5 in which is connected the lateral extension 6, which usually projects adjacent the front of the stove 20 where it is suitably connected to the gas main (not disclosed in the drawing).

Upon the bevelled seat 4 of the burner is 25 adjustably mounted a spreader member 7, preferably of conical shape, its bevelled edges 8 co-acting with the seat 4, the outer face of said spreader being preferably wider than the outer circumference of said seat 4, said spreader also having a downward central de- 30 pending tubular member 9, inwardly threaded adapted to receive the threaded end of the upright spindle 10, which is fixedly secured in the bottom or lower re-inforced wall 11 of the burner.

35 On the upper flat surface of the spreader 7 is preferably provided a square hole 12, by means of which the spreader may be adjusted by inserting a suitable tool therein.

To provide for a firm and precise adjustment of the spreader, a spiral spring 13 is 40 provided around the spindle 10, said spring abutting at one end against the inner side of the spreader and at its other end against the bottom of the burner, so that a constant pressure against said spreader will be provided, to lock same in adjusted position.

What I claim as my invention is:—

In a burner of the character described, 45 means for controlling the egress of air and gas mixture from said burner, said means

comprising a spreader having on its inner side a depending inwardly threaded tubular member and a centrally disposed square hole in its outer surface, a rod fixedly secured in the bottom of said burner at one end and suitably threaded at its other end to engage in said threaded tubular member, and a spiral spring wholly located within said burner mounted around said rod and tubular member and adapted to press said spreader apart from the exit of said burner.

Signed at Montreal, Quebec, Canada, this 14th day of June, 1928.

JOHN HENRY BEEBY.
